(57) **CLAIM**

The ornamental design for a display screen or portion thereof with transitional graphical user interface, as shown and described.

DESCRIPTION

FIG. 1 is a front view of the first image in a sequence of a display screen or portion thereof with transitional graphical user interface showing my new design according to a first embodiment;

FIG. 2 is a front view of the second image thereof;

FIG. 3 is a front view of the third image thereof;

FIG. 4 is a front view of the fourth image thereof;

FIG. 5 is a front view of the fifth image thereof;

FIG. 6 is a front view of the sixth image thereof;

FIG. 7 is a front view of the first image in a sequence of a display screen or portion thereof with transitional graphical user interface showing my new design according to a second embodiment;

FIG. 8 is a front view of the second image thereof;

FIG. 9 is a front view of the third image thereof;

FIG. 10 is a front view of the fourth image thereof;

FIG. 11 is a front view of the fifth image thereof; and,

FIG. 12 is a front view of the sixth image thereof.

The outer perimeter broken lines in the drawings represent a display screen or portion thereof and form no part of the claimed design.

The remaining broken lines in the drawings illustrate portions of the graphical user interface which form no part of the claimed design.

The appearance of the transitional graphical user interface sequentially transitions between the images shown in FIGS. 1 through 6 and in FIGS. 7 through 12, respectively. The process or period in which one image transitions to another forms no part of the claimed design.

The grayscale portions shown within the drop arrow in FIG. 1 and the vertical slide bar on the lower-right side of FIGS.

(Continued)

1-6 form part of the claimed design. The grayscale tones in the drawings represent a contrast in appearance that forms part of the claimed design.

1 Claim, 12 Drawing Sheets

FIG. 5

FIG. 5 illustrates a user interface for a learning management system. The interface includes a header with the text "Launch activity" and "Staff Leave" (with a dropdown arrow). Below this, there are four learner status indicators: "Learner(s)" (25%), "Learner(s)" (25%), "Learner(s)" (25%), and "Learner(s)" (25%). Each indicator is associated with a grade: "Excellent" (25%), "Very Good" (25%), "Good" (25%), and "Average" (25%).

The interface features a "Status" button and a "Grade" button. Below these buttons is a search bar labeled "Type Student name" with a magnifying glass icon. To the right of the search bar are three dropdown menus: "Scale" (with options "A" and "Excellent"), "Proficient" (with options "Yes" and "No"), and a third dropdown menu (partially visible) with the text "Student Name" and "Health and Safety".

Below the search bar, there are three student entries, each with a circular profile icon and the text "Student Name" and "Health and Safety". The first student entry shows "Excellent" and "Yes". The second student entry shows "Good" and "Yes".
